UNITED STATES PATENT OFFICE.

ALBERT H. WADELL, OF NEWARK, NEW JERSEY,

MACHINE FOR FACING THE BEARINGS OF CONNECTING RODS.

Application filed May 28, 1924. Serial No. 716,390.

To all whom it may concern:

Be it known that I, ALBERT H. WADELL, a citizen of the United States, and a resident of Newark, county of Essex, and State 5 of New Jersey, have invented certain new and useful Improvements in Machines for Facing the Bearings of Connecting Rods, of which the following is a specification.

This invention relates to an improved machine for facing the bearings of connecting rods and while the machine is adapted for other purposes, that is, it can be used in facing articles other than connecting rods, it will be described herein as a machine particularly adapted for facing the bearings 10 of connecting rods.

The machine is one in which the connecting rod is supported so that it can be rotated as a crank, being supported so that it 20 can freely revolve the supporting means of the connecting rod projecting from one face of the machine so that a tool mounted in the fixture can be adjusted along the face of the connecting rod so as to finish it and 25 the tool being also adjustable when necessary to adjust it to vary the penetration of the tool into the material on which it is operated.

The invention is illustrated in the accompanying drawings, in which Figure 1 30 is a face view of the machine made according to my invention with a connecting rod mounted on it. Figure 2 is a top view with the tool and tool holder removed. Figure 3 is a vertical section on a large scale on line 3—3 in Figure 1. Figure 4 is a section on line 4—4 in Figure 3. Figure 5 is a front view of the tool holder removed from the fixture and with the tool mounted therein. Figure 6 is a bottom view of the tool 40 holder with the tool in it. Figure 7 is a perspective view of the tool used with the tool holder. Figure 8 is a perspective view of one of the jaws in the expansible mandrel. Figure 9 is a detail section showing the tool 45 operating on the face of the connecting rod bearing and Figure 10 is a detail perspective showing how the tool is used for finishing and rounding the inner edge of the bushing in the bearing.

The machine is mounted usually on a workbench 10 and is fixed in place so that it is rigid so that it retains its place under the leverage of rotating the connecting rod 50 against the tool. The device comprises a fixture 11 which has a bearing 12 in the lower portion and standards 13 at the side

above the bearing and a cap 13^a at the top.

The bearing is used for mounting a freely rotating expansible mandrel and in the form shown the shaft 14 is held against longitudinal movement at one end by a nut 15 and at the other end by the collar 16 of the mandrel, the shaft having on its outer end a collar 17 which is movable along the mandrel and can be forced inward by the 60 nut 18 on the screw-threaded end 19 of the shaft 14.

The faces of the collars 16 and 17 incline inwardly, that is, they converge toward the centre of the mandrel and are slotted as at 70 20. In each of these slots is a jaw 21 with ends 22 inclined to fit the angle of the collars 16 and 17 so that when the nut 18 is screwed on, the jaws all move outward and are thus adapted to grip the inner wall or 75 face of the bushing 23 and the bearing 24 of the connecting rod 25, the inside of the bushing having been rounded and being thus accurately centred when the jaws 21 are forced outward in contact with it. 80

To provide for the free and easy rotation of the connecting rod it is usual to project the handle 26 from the small bearing 27 on the connecting rod so that the handle 26 permits the rotation of the connecting rod 85 as a crank. The tool that is to face the end of the bushing 23 or, if there is no bushing, to face the bearing 24 is mounted in a fixture, usually in a tool holder 28, the tool 29 being slidable in the tool holder being 90 arranged in a slot which is closed at the bottom by a plate 30 held on by screws 31.

The tool holder 28 is raised and lowered by the screw 32 which passes through a screw-threaded opening 33 in the cap 13^a 95 and has a wheel 34 for turning it. The collar 35 at the end of the screw is fastened by the nut 36 so that the collar raises and lowers the tool holder 28 as the screw 32 is turned. The tool holder slides between the uprights 13 and is prevented from turning by having its front and rear edges 37 projecting slightly to the side at the front and back of the fixture. 100

The tool is moved in the tool holder by the screw 38 operating in the screw-threaded opening 39 in the tool holder 28 and having a collar 40 rotating in the notch 41 in the back end of the tool 29. 105

The tool to finish the bearings is preferably made with a substantially perpendicular cutting edge 42 which projects from the 110

end of the tool 29 but the top edge is curved as at 43 merging with the vertical edge 44. The edge 42 is used, as shown in Figures 3 and 9, for operating on the face of the bushing or bearing by adjusting the tool as shown in Figure 3 and then turning the connecting rod like a hand crank and operating the wheel 34 and the screw 38 to give the proper travel and penetration to the tool.

When the tool is approaching the inner edge of the bearing if it is to be rounded as shown in Figure 10, the tool can be advanced by the screw 38 and also by the screw 32 when necessary to cause the rounded edge 43 of the cutter to provide the rounded finished corner at the ends of the bushing.

It will be evident, therefore, from this description that when a bearing or a connecting rod is to be faced it is placed on the freely revolvable mandrel and while the workman turns the connecting rod as a crank at one end, he makes such advances and adjustments through the handle 34 and the screw 38 to cause the tool to finish the face of the bearing to the desired degree and when the work is finished by retreating the nut 18 the jaws of the mandrel are retreated and the connecting rod is removed from the device.

When the connecting rod is removed from the mandrel the jaws 21 are kept from falling out by a spring 45 which is very light for the reason that it does not resist the expansion of the jaws 21 and is only strong enough to hold them against the collars 16 and 17.

I claim:

40 1. A machine for facing the bearings of

a connecting rod comprising a fixture, a freely rotatable expandible mandrel to clamp the inside of the bearing of a connecting rod, an adjustable tool holder in the fixture, and a tool in the tool holder and disposed so that it can be placed in engagement with the face of the bearing of the connecting rod.

2. A machine for facing the bearings of a connecting rod comprising a fixture with a freely rotatable mandrel projecting from the front thereof to clamp the inside of the bearing of the connecting rod, a tool, and an adjustable tool holder to hold the tool on the rear face of the said bearing whereby when the bearing on the mandrel is rotated as a crank the tool can be caused to traverse the face of the bearing.

3. A machine for facing the bearings of a connecting rod comprising a fixture, a tool holder adjustable in the fixture, a tool in the holder, and a freely rotatable mandrel on the fixture and projecting beyond the tool whereby a connecting rod bearing can embrace the mandrel so that when the connecting rod is operated as a crank the tool can be adjusted to operate on the face of the bearing.

4. A machine for facing the bearings of a connecting rod comprising a fixture having a horizontal bearing therein, a freely rotatable shaft in the bearing, an expandible mandrel on the projecting end of the shaft, a tool in the tool holder, a tool holder adjustable vertically, and means for horizontally adjusting the tool in the holder.

In testimony that I claim the foregoing I have hereto set my hand this 27th day of May, 1924.

ALBERT H. WADELL.
